UNITED STATES PATENT OFFICE.

WILLIAM H. CLARK AND WILLIAM J. CLARK, OF SALEM, OHIO.

IMPROVEMENT IN FLUID-MEASURES AND PUMPS COMBINED.

Specification forming part of Letters Patent No. 179,096, dated June 27, 1876; application filed May 3, 1876.

To all whom it may concern:

Be it known that we, WM. H. CLARK and WM. J. CLARK, of Salem, in the county of Columbiana and State of Ohio, have invented certain new and useful Improvements in Fluid-Measures and Pumps Combined; and we do hereby declare that the following is a full and complete description of the same, reference being had to the accompanying drawings, making part of this specification, in which—

Figures 1 and 2 are side views of the apparatus. Fig. 3 is a transverse vertical section.

Like letters of reference refer to like parts in the several views.

The above said invention is a pump for drawing oil and other liquids from barrels, tanks, and other vessels, and operating in connection therewith is a measuring device, whereby any certain fractional amount of the contents of the barrel may be obtained without the use of ordinary measures for that purpose. For a more full and complete understanding of the invention reference will be had to the following detailed description.

The pump alluded to consists of the barrel or tube A, Fig. 3, of which B is the pump-rod; C, the valve attached thereto, and operated from the outside by a button, D. In the lower end of the pump barrel or tube A is a stationary valve, E, all of which are constructed and operated as an ordinary lifting-pump, or may be.

The pump-barrel A is fitted telescopically in a tube, F, so that it can be extended therefrom or drawn therein as the depth of the barrel or other vessel may require, in order that it may reach the contents, while by means of this device the head or measuring apparatus remains at a convenient height for operating it.

The tube F referred to passes through the center of a receiver, G, and is secured to the top of the inside thereof, by soldering or otherwise, immediately under the stuffing-box H, Fig. 3, whereby the pump-rod is made tight. The tube is secured in the bottom of the receiver by a stuffing-box, I, into which is screwed a follower, J. It will be observed, on examination of Fig. 3, that the tube is smaller than the diameter of the follower through which it passes; hence, to enlarge it, so that

it may fill the follower, or nearly so, lugs a are secured to the side of the tube, which project so far as to reach to the sides of an overflow or gage tube, K, put on over the tube F, passing between the lugs a thereof and the side of the follower, as shown in Fig. 3.

The overflow or gage tube K fits closely, but not tightly, in the stuffing-box I and over the lugs a of the tube F, (suitable packing being used in the stuffing-box around the tube K to prevent leakage,) and is steadied in position at its lower end by a collar, L, or its equivalent, which is attached to the receiver by suspension-rods Q, substantially as shown in the drawings.

The gage-tube K may be moved up or down to obtain the required adjustment for measuring any desired quantity, either with the hand or by means of a screw or other well-known mechanical appliances, among which the rack and pinion M N, as shown, afford a cheap and quick-acting device.

The gage-tube K, with its means of adjustment, or their equivalents, as described, viz: the stuffing-box I and follower J, collar L and rods Q, rack and pinion M N, may also be attached to and used to regulate the capacity of elevated tanks or other vessels independently of any pumping device. When used, however, in combination with a pump barrel or tube, F, we prefer to have the gage-tube surround the pump-barrel, as shown, in order that greater compactness in the device may be secured thereby.

Having described the construction and arrangement of the apparatus, the operation of the same is as follows: The pump-barrel A F is extended to its full length and inserted in the tank or other vessel until the lower end of the pump-barrel reaches the bottom, when by a downward pressure upon the receiver or upper section of the device the tube A is telescoped into the tube F, and the pump-barrel shortened thereby until the collar R rests in the bung-hole of the vessel, (or the support provided for it,) and the receiver is thus brought within convenient distance for operating it; or the pump-barrel may be adjusted before placing it into the vessel to the proper length for withdrawing the fluid without disturbing the sediment that may have collected

in the bottom. The gage-tube K should then be adjusted by means of the rack and pinion M N, (or their equivalents, as described,) and a graduated scale, d, so as to limit the capacity of the receiver to the fractional part required to be withdrawn from the contents of the vessel. The fluid is then pumped into the receiver through the openings e, Figs. 2 and 3, in the upper end of the tube F, until the receiver is filled to a level with the top of the gage-tube K. The surplus arising from careless pumping will flow over the end of the gage-tube and run back into the vessel from which the fluid is being withdrawn, leaving in the receiver only the quantity for which the gage-tube has been specially adjusted. The fluid thus measured may then be drawn off into the vessel to be filled by means of a faucet, A'. When the gage-tube is used in combination with an elevated tank or vessel (whether directly connected with a pump, as shown, or entirely independent thereof) it may be ad-

justed to restrict its capacity to a desired quantity, or the upper end of the tube may be raised to the top of the vessel and the latter filled full, when by lowering the gage-tube any desired quantity may be drawn off through it into other vessels requiring to be filled.

What we claim as our invention, and desire to secure by Letters Patent, is—

1. A pump barrel or tube, A F, when made in two or more parts telescopically arranged, for the purpose set forth, and in the manner substantially as described.

2. In combination with a receiver or elevated vessel, G, an adjustable gage-tube, K, substantially as described, and for the purpose specified.

WILLIAM H. CLARK.
